MULTIPLE CONTROL APPARATUS FOR ELECTRIC RAILWAYS.

1,411,269.

Specification of Letters Patent.

Patented Apr. 4, 1922.

Application filed April 16, 1919. Serial No. 290,550.

To all whom it may concern:

Be it known that I, ABRAHAM COUWENHOVEN, a subject of the Queen of the Netherlands, residing at No. 132 Zurcherstrasse, 5 Höngg, near Zurich, Switzerland, have invented certain new and useful Improvements in Multiple Control Apparatus for Electric Railways, of which the following is a specification.

- 10 In multiple control apparatus for electric railways with motor-driven main switch drums, it is well known that the problem to be solved consists in moving from a single but optional control station all the main switch drums of the several motor vehicles each time on to a determined switch contact predetermined by the control station. In such an operation the motors serving for driving the main switch drums are 15 placed in circuit by means of the controlling drum situated at the control station and operated by the driver, but they have to move automatically out of circuit again after the predetermined switch contact has 20 been reached. This problem has already been solved in various ways, but the solutions have always required a number of rather complicated devices in order to satisfy all requirements.
- 25 The present new solution of the said problem has the advantage of being extremely simple. Although the number of the several devices could not be diminished appreciably as compared with the known control apparatus yet however the several parts belonging to the improved control apparatus have 30 lost their complicated construction and have become simple, powerful and cheap apparatus.
- 35 The essential feature of the invention consists in this that the controller drum is provided with two segments which are staggered in step-like stages in the usual way, and that the switch motor of each motor vehicle is controlled by means of relays. The controller drum is provided as usual with a series of fixed contacts equal to the 40 number of the steps. These steps are connected electrically to an equal number of leads extending along the train, and are also connected electrically in each motor vehicle to an equal number of contacts of an answering device contact roller or path that is actuated also by the switch motor.
- 45 In every position of the controller drum

one portion of the through leads is connected to the positive covering of the controller drum, whilst the other portion of the through leads is connected to the negative covering of the controller drum. Experience has shown that the controlling motor runs until the contacts of the answering device actuated by it, have reached the limit position of positive and negative.

The invention will now be described with reference to the drawing which illustrates a constructional example of the improved control apparatus for six switch steps. The drawing shows the control station in operation and in connection with the main switch drum drive of a motor vehicle. The through control leads, as well as the fixed contacts connected to them, are marked with Arabic numerals 1-6; further, the two through main leads + and -, as well as the leads for forward and reverse running V and R are also provided. The switch positions of the control drum and answering device are correspondingly marked with the Roman numerals I-VI. The zero positions are marked 0; the cut-out position of the controller drum into which are to be brought all the drums of the control stations that are not in service are marked A. The control circuit extending through all the vehicles of the train is completely separated from that of the motor *a* which drives through the gearing *b*, the slip coupling *c* and the chain gear *d*, the main switch drum that is mounted on the shaft *e*, and by means of this separation the through leads are relieved of the comparatively heavy currents of the motor drives, so that they as well as the lead couplings *f*, have to be calculated simply for carrying the very small controlling currents for the relays *g* and *h*.

The controller drum *i* is interlocked with the commutator switch *k* in such a manner that the latter cannot be moved out of its mid-position so long as the controller drum *i* is in the position A, and also that the controller drum *i* cannot be moved out of the position 0 into a running position (I-VI) so long as the commutator switch *k* is in its mid-position. This has however nothing to do with the invention, nor does the invention include the means for driving the main switches for reversing the direction of the running, so this drive is not shown in the drawing. The controller drum

- i* is provided with two stepped segments *m* and *n*, of which *m* is connected to the positive lead + and the other *n* is connected to the negative lead —. In every running 5 position (for instance III), the leads are connected to the + segment *m* up to the Arabic numeral that corresponds to the Roman position numeral (that is to say, in the example the leads 1, 2, and 3), whilst the leads 10 having higher numerals (4, 5, 6) are connected to the — segment *n*. According as the + or the — coil of the relay *g* is energized, the reversing switch *o* will be moved over to the right or to the left, and either 15 the field winding *p* for forward rotation, or the winding *q* for reverse rotation of the motor *a*, is fed with current. At the same time one of the coils of the relays *h* is energized, and the circuit of the locking magnet *r* is connected to the source of power, so 20 that it will attract the pawl *t* and together with the switch *s* will close the circuit of the motor *a*.
- As above stated, the shaft of the switch 25 motor *a* serves to drive the answering device *l* which in this case is constructed by way of example as a straight switch path and is provided with contacts 1-6 and with two sliding brushes *u* and *v* that are insulated from each other and are slidably mounted on a screw spindle, as well as with two slide bars *x*, *y*. 30
- If, according to the above example, the controller drum *i* is rotated into the position 35 III, this movement will connect the controller leads 1, 2, 3 to the + segment *m*, and the leads 4, 5, 6 to the — segment *n* of the drum. When the brush *v* of the answering device *l* is not placed on a connecting 40 contact, it cannot close any circuit. On the contrary, however, the controller circuit is closed by the brush *v* of the device *l* which connects the contact 1 (connected to the positive + lead) to the upper slide bar *y* through the — coils of the relays *g* and *h*. The magnet *r* is brought into circuit and 45 attracts the pawl *t* from engagement with the notched disc *w*, and it, together with the switch *s*, closes the circuit of the motor *a* whose field winding *q* has been included in the circuit by the relay *g*. The motor commences to run, and drives, in addition to the main drum spindle *e*, also the screw spindle of the answering device *l*. By this 50 means the brushes *u*, *v* are moved towards the right. The controller circuit is opened and the relays *g* and *h* become dead. But whilst the switch *o* of the relay *g* remains closed to the left, the switch of the relay *h* is moved by the spring power into the cut-out position (as shown). The relay magnet *r* is then de-energized, but the switch *s* cannot open the circuit of the controlling 55 motor *a* until the complete revolution of the spindle *l* allows the projection on the pawl *t*

to fall into the notch provided in the periphery of the disc *w*. After the completion of the revolution, the brush *v* has moved on to the contact 2, whereby the circuit of the locking magnet *r* is closed again 70 and the pawl *t* is attracted until the notch in the disc *w* has moved past under it. At the same time the brush *u* has moved over upon the contact 1, but does not close any circuit in this position, because the lower 75 bar *x* is connected to the + pole, as is likewise the case with the contact 1. The same series of operations is repeated when the brushes move off the contacts 1, 2 on to the contacts 2, 3 because also the contact 80 3 is connected to the positive (+) pole of the source of power.

An alteration takes place only when the brush *v* moves on to contact 4 which is connected to the negative (—) segment *n* of the control drum *i*. Now no circuit can be closed even by the brush *v*, because the upper slide bar *y* of the answering device *l* is now likewise connected to the negative (—) pole; the relays *g* and *h* remain dead; 90 *h* remains in mid position; and the pawl *t* drops into the notch in the disc *w* immediately it reaches the top point, so that the main switch drum stops exactly at the proper point, whereby the motor *a* is cut out 95 at *s* and is braked by the slip coupling *e*. If the controller drum be rotated to higher controlling steps, the sliding brushes of the answering device will follow each time until there is no longer any potential difference 100 at their two contact surfaces, that is to say, until the brush *v* has become connected on both sides to the + pole, and the brush *u* has become connected on both sides of the — pole. The same is the case when the controller drum *i* is rotated back from a higher 105 stage to a lower stage. Only, in this case the controlling current does not pass any longer through the brush *v* and the upper bar *y* to the — coils of the relays *g* and *h*, but it 110 now passes through the brush *u* and the lower bar *x* to the + coils of the relays, so that now the switch *o* of the relay *g* is thrown over, and the motor *a* will run in the reverse direction again and continue so running 115 until the brushes *u*, *v* come into direct connection with unlike-pole segments *m*, *n* of the controller drum *i*.

As above stated, the answering device may also be constructed differently from that shown; for instance it may have a round contact path or be formed as a switch drum. The relays also are indicated only in a diagrammatic manner and may be constructed differently; in particular the relay *h* may have a single core and a single switch contact. Likewise, the construction of the other switch devices may be modified; further apparatus and locking devices may be added according to the special re- 120 125 130

quirements of the working of each installation. If the main switch drum has brake positions, these may be included in the improved apparatus without further trouble.

5. What I claim is:—

motor circuit will remain closed until in consequence of the displacement of the contact surfaces of the answering device, both coils of both relays are connected at both 5 terminals with the same pole of the power circuit and therefore remain de-energized.

7. In combination in a multiple control apparatus for electric control of railway vehicles, a controller drum, a plurality of controlling motors, a plurality of answering devices for the automatic duly timed cutting out of the controlling motors, a pair of contact surfaces on the controller drum, a pair of contact surfaces on each of the answering devices, one of every pair of contact surfaces being insulated from the other and connected to one pole of the net, the other of every pair being connected to the opposite pole of the net, the controlling circuit being completely separated from the other circuits of the vehicle, the controlling circuit alone extending throughout the entire length of the train, while the circuits of the driving motors are 10 completely separated from the other circuits of the vehicle.

8. In combination in a multiple control apparatus for electric control of railway vehicles, a controller drum, a plurality of controlling motors, a plurality of answering devices for the automatic duly timed cutting out of the controlling motors, a pair of contact surfaces on the controller drum, a pair of contact surfaces on each of the answering devices, one of every pair of contact surfaces being insulated from the other and connected to one pole of the net, the other of every pair being connected to the opposite pole of the net, the controlling circuit being completely separated from the other circuits of the vehicle, the controlling circuit alone extending throughout the entire length of the train, while the circuits of the driving motors are 15 completely separated from the other circuits of the vehicle.

In testimony whereof I have signed my name to this specification.

ABRAHAM COUWENHOVEN.
